His Attorney.

UNITED STATES PATENT OFFICE

HERMAN J. HUBER, OF UPPER DARBY, PENNSYLVANIA, ASSIGNOR TO GENERAL ELECTRIC COMPANY, A CORPORATION OF NEW YORK

METAL INCLOSED ELECTRICAL APPARATUS

Application filed November 29, 1930. Serial No. 499,086.

My invention relates to metal inclosed electrical apparatus and more particularly to means for bracing electrical conductors in metal clad switchgear against large short circuit stresses, as at connections requiring flexible connections between a cable and an insulating bushing of brittle material.

In bus and switch stations of the so-called metal clad type wherein the individual phase connections are encased or armored by a grounded metallic sheathing, the short circuit stresses, particularly in high voltage stations of large capacity, may be of such magnitude that the conductors or cables within the metal sheathing are given a powerful longitudinal thrust or "kick" tending to damage the connections at the brittle porcelain insulating bushings leading from the cable connections to the circuit breakers and other apparatus in the station. In these large stations the conductors or cables are generally of such large size and great weight that it is not practical to connect them directly to porcelain shells or insulators inside the metal inclosures. The general practice is to insert a connection of flexible braid or flexible cable at the point where the heavy conductors join the porcelain shells or insulators. The heavy conductors, therefore, are free to move a limited extent inside of the inclosing casing with respect to the porcelain insulators without causing damage thereto in the event of a heavy short circuit. Heretofore, the metal inclosed conductors have been supported and mounted by spacing collars and similar devices depending mainly on the friction between the same and the inclosing casing for preventing movement of the conductor. While such an arrangement may be satisfactory for lower capacity stations, due to the fact that the short circuit stresses in this case are not of such magnitude as to cause appreciable movement of the spacing collars, the same is ineffective for high capacity stations such as 2½ millions kw.-a. capacity for instance.

In the event that the heavy conductor is not adequately braced or held in its proper position, "chattering" may result due to the vibration permitted by the insecure bracing.

This is considered by operating companies to be an objectional feature since on heavy currents the chattering may be continuous. Furthermore, a heavy short circuit may tear the flexible connection from the top of the shell or break the porcelain unless the conductor at the other end of the flexible connection is firmly secured in position.

A further consideration with respect to the bracing structure for the heavy conductor is that of creepage distance; that is, the distance along the insulating parts between the live conducting portions and the grounded metal casing. In order to have a large factor of safety, this creepage distance should be a maximum for the design involved. It follows, therefore, that the most advantageous design combines maximum creepage distance with maximum bracing effect on the conductor.

A principal object of my invention is the provision of improved means for bracing a metal encased heavy conductor with respect to large short circuit stresses which shall be simple in construction and in application.

A further object of my invention is the provision of improved bracing structure for metal clad conductors which is effective positively to brace the conductor with respect to either tension or compression short circuit stresses and which involves a maximum creepage distance.

My invention will be more fully set forth in the following description referring to the accompanying drawings, and the features of novelty which characterize my invention will be pointed out with particularity in the claims annexed to and forming a part of this specification.

Referring to the drawings, Fig. 1 is a fragmentary elevational view, partly in section, along the line 1—1 of Fig. 2 of metal clad switchgear embodying my invention, and Fig. 2 is a cross sectional plan view taken along the line 2—2 of Fig. 1.

The portion of metal clad switchgear shown in Fig. 1 comprises a metallic inclosing casing 1, as a casting, suitably connected to a metallic pipe or sheathing 2 inclosing the heavy insulated conductor or cable 3. In

general practice, the metallic inclosing structure is filled with oil or other suitable insulating material and the connections are sealed as by a suitable gasket 4 so as to be fluid tight. The lower part of the casing 1 may be connected through the hollow insulator shell 5 constructed of porcelain or the like, to electrical apparatus as circuit breakers or disconnecting switches in a manner well known 10 in the metal clad art. A cylindrical insulating shield 6 may be interposed between the insulator shell and the metallic casing 1.

For the purpose of flexibly connecting the heavy cable 3 to the conducting portion 7 mounted on and extending through the insulator shell, flexible braid conductors 8 are used, the same being bolted or otherwise suitably secured to the interconnected parts as better shown in Fig. 2. Accordingly, a limited amount of movement of the porcelain shell with respect to the cable, as by contraction or expansion due to temperature change, is permitted without causing any damage to the brittle porcelain shell.

25 The bracing means for the cable 3 comprises a frame construction of strong insulating material as wood and is arranged within the casting 1 so that longitudinal thrusts of the cable 3 in either direction are transmitted directly through the bracing structure to the casting. To this end the bracing frame is interposed between the conductor 3 and the walls of the inclosing casing so that the abutting surfaces are substantially in the direction of thrust of said conductor.

The bracing structure in the present instance comprises an A-frame having two legs 9 and 10 suitably connected at one end as by the bolts 11 and braced by the cross member 12 to complete the A-frame. The diverging ends of the legs 9 and 10 are beveled to abut firmly the inner side of the casting 1 as shown, and the connected ends abut the wall or web 1' of the casting so that the structure is rigidly positioned with respect to the casting. The connection between the conductor 3 and the bracing structure comprises a pair of rigid metallic strips 13 and 14 which are bolted as at 15 to the end 3' of the conductor 3 and to mid-portions of the legs 9 and 10 as at 16 and 17 respectively. Accordingly, the conductor is positively braced against longitudinal movement in either direction, tension 50 on the strips 13 and 14 tending to wedge the legs 9 and 10 into firmer engagement with the casting and compression on the strips forcing the converging portion of the A-frame against the wall 1'. Since the cross member 12 prevents relative movement of the legs 9 and 10 and therefore prevents any lateral movement of the A-frame within the metal casing, the bracing structure is equally effective for both compression and tension 65 stresses.

The upper part of the casting 1 is provided with a cover plate 18 for sealing the casting after assembly or inspection. The bracing structure may be assembled and secured in position within the casting 1 without difficulty through the opening in the casting since the A-frame may be readily bolted or secured together within the casting and thereafter connected by the strips 13 and 14 to the conductor 3.

It will be noted that the creepage distance from the ends of the metal strips 13 and 14 which are connected at 16 and 17 respectively to the bracing structure is practically a maximum for the particular design involved. That is, the connection to each of the legs 9 and 10 is substantially at mid-portions so that the distance to the nearest portion of the grounded casing is substantially the same in all cases and is sufficient to prevent flash-over under most severe operating conditions.

It shall be understood that my invention is not limited to specific details of construction and arrangement thereof herein illustrated, and that changes and modifications 90 may occur to one skilled in the art without departing from the spirit of my invention.

What I claim as new and desire to secure by Letters Patent in the United States is:

1. In metal inclosed electrical apparatus including metallic inclosing structure and an electrical conductor mounted therein, means for bracing and holding said electrical conductor with respect to longitudinal movement thereof comprising an insulating frame rigidly mounted within said structure, and means for securing said conductor to said frame so that longitudinal thrusts of said conductor in either direction are transmitted directly by said frame to said structure.

2. In metal inclosed electrical apparatus including a metallic inclosing structure and an electrical conductor mounted therein, means for bracing and holding said electrical conductor with respect to longitudinal movement comprising an insulating frame disposed substantially in the same plane as the longitudinal axis of said conductor, said frame being rigidly mounted within and abutting the walls of said structure, and means for securing said conductor to said frame so that longitudinal thrusts of said conductor in either direction are transmitted directly by said frame to said structure.

3. In metal inclosed electrical apparatus including a grounded metallic casing and an electrical conductor mounted therein, means for bracing said electrical conductor against large short circuit stresses tending to cause longitudinal movement of said conductor comprising an insulating A-frame abutting and rigidly mounted within said casing, the abutting surfaces of said frame being substantially in the direction of the trust of said conductor, and means for rigidly securing

- said conductor to an intermediate portion of said A-frame so that longitudinal movement of said conductor in either direction is prevented.
5. Metal clad electrical apparatus comprising a grounded metallic casing, a comparatively massive electrical conductor spaced from and mounted within said casing, an insulating shell of comparatively brittle material mounted within said casing, a conducting portion mounted on said insulating shell, said conductor and conducting portion being electrically connected by flexible conductors for precluding transmission of shock from 10 said conductor to said insulating shell, and means for bracing and holding said conductor with respect to longitudinal movement due to heavy short circuits comprising an A-frame of insulating material abutting and 15 rigidly mounted within said casing, the abutting surfaces of said frame arranged so as to directly oppose the thrust of said conductor, and metallic means for rigidly securing an end of said conductor to an intermediate portion of said frame so that longitudinal movement of said conductor in either direction is 20 prevented and a large creepage distance between said securing means and said grounded casing is obtained.
- 25 5. Metal clad electrical apparatus comprising a grounded metallic casing, a comparatively massive electrical conductor spaced from and mounted within said casing, a porcelain insulating shell mounted within 30 said casing and extending substantially at right angles to said conductor, a conducting portion mounted on said insulating shell, said conductor and conducting portion being electrically connected by flexible braided 35 conductors for precluding transmission of shock from said conductor to said insulating shell, and means for bracing and holding said conductor with respect to heavy short circuit 40 thrusts comprising an A-frame of insulating material abutting and rigidly mounted within 45 said casing, said frame being interposed between said conductor and said casing in the direction of thrust of said conductor, and rigid metallic strips for securing said conductor at said flexible connection to an intermediate portion of said frame substantially 50 midway between the abutting surfaces of said casing so that longitudinal movement of said conductor in either direction is prevented, said frame having a large creepage 55 distance between said metallic strips and the abutting surfaces of said grounded casing.

In witness whereof, I have hereunto set my hand this 26th day of November, 1930.

HERMAN J. HUBER.
